ADJUSTABLE TRIP FOR POSTAL MACHINES

Filed Jan. 21, 1929

UNITED STATES PATENT OFFICE

WILBUR C. ALLEN, OF LOS ANGELES, CALIFORNIA, ASSIGNOR, BY MESNE ASSIGNMENTS,
TO RALPH C. WHITLOCK PATENTS, INC., A CORPORATION OF NEVADA

ADJUSTABLE TRIP FOR POSTAL MACHINES

Application filed January 21, 1929. Serial No. 333,904.

The device of the present invention provides for the selective positioning of mechanically conveyed articles with respect to a fixed station at which some action may be performed upon the article, and is particularly designed for use in a mail marking machine, having a power driven conveyor, to stop the conveyor, and hence the letter carried thereby, in various positions with respect to a printing means whereby the printed indicia may be selectively positioned upon the letter.

Among the objects of my invention is to provide an adjustable trip forming part of a conveyor control whereby to print indicia at various predetermined positions on mail pieces; to provide a carriage for the trip which supports and positions same with respect to an actuating element of the conveyor control; to construct a trip lever having a fulcrum affording universal movement whereby to provide for movement of the trip lever in the path of an envelope as carried on a conveyor to affect, momentary stoppage of the envelope for a printing interval and provide for movement of the trip lever out of the path of the envelope to affect starting of the envelope for discharge of the printed envelope and the supply of a succeeding envelope, and to provide a trip of simple, durable and inexpensive construction which will act in a manner to offer minimum resistance to the travel of the envelope.

To the above purposes my invention consists in the novel construction, arrangement and combination of parts as hereinafter fully clearly and concisely described, definitely pointed out in my claims and illustrated by the accompanying drawings (1 sheet) in which—

Fig. 1 is a side elevation, partly in section, of the trip arm and its supporting carriage.

Fig. 2 is a sectional elevation from the front at 2—2 in Fig. 1, showing the spring support and stop.

Fig. 3 is a diagrammatical front elevation showing in dotted lines the travel of the trip.

Fig. 4 is a plan view of the trip and travel in a central position, the travel of the trip from same being shown in broken lines, and a second position of the trip and carriage

being also shown in broken lines and the travel of the trip from the carriage being further shown in broken lines.

Fig. 5 is a more or less diagrammatic front elevational view of my device as viewed from the right hand side looking left in Fig. 1.

The carriage 10 is fulcrumed at 11 by fastening 12 so that it may be moved laterally to vary the intercepting point of the trip arm 13 with mail pieces.

The carriage 10 carries at its front end an engaging member 10' to facilitate manual adjustment; and toward the fulcrum point a frame 14 is securely fastened to the carriage and which supports the trip lever 15 with a universal joint as at points 16 and 17. Said frame 14 at its front end forms stop 18, and spring hanger 19 to which is hung one end of tension spring 20 the other end of which spring is hung on arm 21 forming a part of the adjustable mounting 22 suitably secured to lever 15. The spring 20 functions through mounting 22 to tension the trip arm 15 so that the forward up-turned section 13 may reside in the path of mail pieces being carried by any suitable conveyor 23, and further functions to return the trip arm 15 to its rest position against stop 18. Fig. 3 shows the cycle of movement of the trip 13 relative to the plane at which mail matter travels on conveyor 23. The guide plate 24 secured to carriage 10 by a support 40 acts to guide the travel of trip 13 down to a point below the letter plane, from where the spring 20 returns it to its original intercepting position. Figs. 1 and 3 show in dotted lines the lower position at 26 of the trip 13.

The opposite end of the trip arm 15 is shaped to a trip 27 which at rest position of arm 15 is approximately in contact with member 28 which may be a conveyor clutch control arm to be actuated by the trip 27.

The point of contact 29 between trip 27 and the member 28 will remain permanent upon any movement of the carriage 10 for the adjustment of the trip 13 relative to its point of contact with mail pieces being carried by conveyor 23.

This trip does not intercept the movement of mail matter upon a conveyor by contact or

friction between it and the mail pieces, but is only actuated by contact with the mail pieces to cause movements of a clutch to stop the conveyor, and may return to its original position at any time when its lateral movement and contact with the guide plate 24 brings it below the letter plane. Fig. 4 shows two positions of the carriage 10 and the full movement of trip 13 and the permanency of contact point 29.

The form of the device illustrated and described herein is submitted in accordance with statutory requirement by way of exhibiting one form of embodiment of my invention. Various changes, alterations or modifications of the structure may be made without departure from my invention as defined in the following claims.

I claim:

- 20 1. A trip device comprising a trip; a mount therefor providing substantially universal movement of the trip and a movable support for the mount providing variable positions for the functioning of the trip.
- 25 2. A trip device comprising a trip lever; a universal movement mount therefor; means for moving an article in a direction providing tripping motion of the lever; means for engagement with the lever to remove it from the path of the article; an adjustable support for the mount providing selective tripping points in the path of the article, and means for restoring the lever after movement by the article.
- 30 3. In a trip device, a pivotally mounted carriage; a frame secured to said carriage; a trip lever mounted for substantially universal movement in said frame; means for moving an article in a direction against said lever to provide tripping motion of the lever; and means for engagement with said lever to remove it from the path of the article after tripping motion has been imparted to said lever.
- 35 4. In a trip device, a pivotally mounted carriage; a frame secured to said carriage; a trip lever mounted for substantially universal movement in said frame; means for moving an article in a direction against said lever to provide tripping motion of the lever; means for engagement with said lever to remove it from the path of the article after tripping motion has been imparted to said lever; and means to normally tension said trip lever in the path of an article moved by said article moving means.
- 40 5. In a trip device, a carriage; means fulcruming said carriage to permit lateral movement of said carriage; a member extending from said carriage and having a stop; a trip lever supported by said member; means normally urging said lever against said stop; and means adapted to be engaged

by said lever to remove it from its normal position for the purpose set forth.

6. In a trip device, a movable carriage; a frame secured to said carriage and having a stop; a trip lever supported by said carriage; and means connected to said carriage and said trip for normally holding said lever against said stop and in the path of articles adapted to contact and operate said trip lever.

7. In a trip device, a movable carriage; a frame secured to said carriage and having a stop; a trip lever supported by said carriage; means connected to said carriage and said trip for normally holding said lever against said stop and in the path of articles adapted to contact and operate said trip lever; and means adapted to move said lever out of the path of the articles operating said trip lever.

In testimony whereof, I hereunto affix my signature this 12th day of January, 1929.

WILBUR C. ALLEN.

CERTIFICATE OF CORRECTION.

Patent No. 1,809,264.

Granted June 9, 1931, to

WILBUR C. ALLEN.

It is hereby certified that the name of the assignee in the above numbered patent was erroneously written and printed as "Ralph C. Whitlock Patents, Inc.", whereas said name should have been Ralph G. Whitlock Patents, Inc., as shown by the records of assignments in this office; and that the said Letters Patent should be read with this correction therein that the same may conform to the record of the case in the Patent Office.

Signed and sealed this 14th day of July, A. D. 1931.

(Seal)

**M. J. Moore,
Acting Commissioner of Patents.**
